UNITED STATES PATENT OFFICE.

RICHARD H. VOIGT, OF MILWAUKEE, WISCONSIN.

FOLDING BOX.

1,272,878.

Specification of Letters Patent. Patented July 16, 1918.

Application filed November 13, 1914. Serial No. 871,866.

To all whom it may concern:

Be it known that I, RICHARD H. VOIGT, a citizen of the United States, and resident of Milwaukee, in the county of Milwaukee 5 and State of Wisconsin, have invented new and useful Improvements in Folding Boxes, of which the following is a description, reference being had to the accompanying drawings, which are a part of this specification.

10 This invention relates to improvements in folding boxes.

It is one of the objects of the present invention to provide a folding box of the type more commonly made of paper board and 15 which is so folded in its flat form that by bending up the side portions of the box the end portions will be automatically swung to open position and may be easily interlocked in open position to said side pieces.

20 A further object of the invention is to provide a folding box in which the portions of the box which are locked together will be securely held against accidental unlocking of the parts.

25 A further object of the invention is to provide a folding box which is of strong and durable construction and in which the minimum amount of stock is used.

A further object of the present invention 30 is to provide a folding box which may be sold or shipped to the user in collapsed form and which may be easily and quickly unfolded for use.

A further object of the present invention 35 is to provide a folding box in which portions of the stock, of which the box is formed, are folded over upon itself to form reinforcing ends or sides for the box.

With the above and other objects in view, 40 the invention consists of the improved folding box and its parts and combinations as set forth in the claims, and all equivalents thereof.

In the accompanying drawing in which 45 the same reference characters indicate the same parts in all of the views:

Figure 1 is a top view of the improved folding box in collapsed position, a portion of the right hand end of the box being bent 50 outwardly to show other portions therebelow.

Fig. 2 is a transverse sectional view of the lower portion of the box taken on line 2-2 of Fig. 6;

55 Fig. 3 is a sectional detail view taken on line 3-3 of Fig. 2;

Fig. 4 is a sectional detail view taken on line 4-4 of Fig. 2;

Fig. 5 is a detail corner view of the box shown in unfolded position; and

Fig. 6 is a longitudinal sectional view of the box and its cover.

Referring to the drawing the numeral 8 indicates the blank from which the box is formed and consists of a sheet of paper 65 board of rectangular form having longitudinally extending parallel side creases of folds 9 and upper and lower transversely extending parallel end creases 10 and 11 which cross the longitudinal or side creases. These 70 folds or creases divide the box blank into a bottom portion 12, side portions or walls 13, end portions or walls 14 and reinforcing end portions 15. The reinforcing end portions 15 are provided with notches 16 75 forming locking flaps 16' which are adapted to interlock with the notched portions 17 of the side ends portions 13 when the box is in open position as shown in Figs. 2 and 6.

In order to permit the side end portions 80 13' being folded at an angle against the end portions 14, the said side end portions are provided with creases or folds 18 which extend diagonally at forty-five degree angles 85 from the four corners of the bottom portion 12 to the notches 16 of the side end portions.

In forming the box the side portions are folded over upon the bottom portion and the reinforcing end portions are then folded 90 over upon the end portions and secured thereto by staples 19 or other desirable means.

It will be noted that the inner edges of the reinforcing ends register with the folded side end notches so that when the end portions are bent upwardly to form the box the sides will be automatically swung upwardly to open position due to the formation of the transverse and diagonal creases. When in open or uncollapsed position the locking 100 flaps are sprung over the notched portions of the side end portions of the blank and the box will be locked in open position. The top or cover 20 for the box is formed in the same manner as the bottom portion and is 105 slightly larger in size to easily slip over the bottom portion. It will also be noted that the construction of the box provides for forming the sides of single thickness of material throughout their length.

110 From the foregoing description it will be seen that the folding box is reinforced on

opposite ends and may be held by the end without breaking and furthermore that the side portions of the box will automatically swing to open position when the ends are 5 unfolded.

What I claim as my invention is:

1. A folding box, consisting of a blank having side and end creases to form bottom, side, end and side side portions and reinforcing 10 end portions having edge notches, the side walls adapted to be folded over upon the bottom portion and the reinforcing end walls folded over upon the end walls and secured thereto, the reinforcing end walls having locking flaps extending approximately 15 parallel to the end creases which engage the edge notched locking parts of the side walls when the blank is opened into box form to form side walls of single thickness of material throughout their lengths.

2. A folded box, consisting of a bottom portion having side walls and end walls connected thereto and notched reinforcing ends connected to the end walls and also having 25 diagonally folded corner portions, the end portions of the side walls provided with edge locking notches and the reinforcing ends having locking flaps extending approximately parallel to the end creases which underlap the diagonally folded end portions of 30 the side walls adjacent to the locking recess and enter said recesses, to form side walls of single thickness of material throughout their lengths.

3. A folding box, consisting of a blank having side creases and transverse creases to form bottom, side, end and reinforcing end walls, the side walls near their ends being provided with locking recesses and being creased on lines extending diagonally from 35 the corners of the bottom portion of the blank to the said recesses, the end walls of the blank being recessed to form transversely extending locking flaps which underlap and engage the diagonally creased 40 portions of the side walls adjacent to the side recesses, the side walls adapted to be folded over the bottom portion and the reinforcing end walls adapted to be folded over the end walls and secured thereto when in collapsed position, said construction permitting the end walls to be bent upwardly and the side walls to be bent upwardly by the 45 movement of the end walls and when in upright position the transversely extending locking flaps underlapping the diagonally creased end portions of the side walls adjacent to the end walls to lock the parts in open position, the side walls of said box being formed of single thickness of material throughout their length.

folded over the bottom portion and the reinforcing end walls adapted to be folded over the end walls and secured thereto and the end walls and the side walls being bent upwardly to positions to permit the engagement of the transversely extending locking flaps with the locking diagonally extending recessed portions, the diagonal 50 creases permitting the end portions of the side walls to engage the end walls when in open position, the side walls of said box being formed of single thickness of material throughout their length.

4. A folding box, consisting of a blank having side creases and transverse creases to form bottom, side, end and reinforcing end walls, the side walls near their ends being provided with locking recesses and being creased on 55 lines extending diagonally from the corners of the bottom portion of the blank to the said recesses, the end walls of the blank being recessed to form transversely extending locking flaps within the marginal edges 60 of the end walls which underlap and engage the diagonally creased portions of the side walls adjacent to the side recesses, the side walls adapted to be folded over the bottom portion and the reinforcing end walls adapted to be folded over the end walls and secured thereto when in collapsed position, said construction permitting the end walls to be bent upwardly and the side walls to be bent upwardly by the 65 movement of the end walls and when in upright position the transversely extending locking flaps underlapping the diagonally creased end portions of the side walls adjacent to the end walls to lock the parts in 70 open position, the side walls of said box being formed of single thickness of material throughout their length.

In testimony whereof I affix my signature in presence of two witnesses.

RICHARD H. VOIGT.
